ATTORNEY

UNITED STATES PATENT OFFICE.

CORNELIUS AMBRUSTER, OF ROSLYN, PENNSYLVANIA.

STORAGE-BATTERY ELECTRODE OR PLATE.

1,354,086.

Specification of Letters Patent. Patented Sept. 28, 1920.

Application filed September 4, 1918. Serial No. 252,529.

To all whom it may concern:

Be it known that I, CORNELIUS AMBRUSTER, a citizen of the United States, residing at Roslyn, in the county of Montgomery and State of Pennsylvania, have invented certain new and useful Improvements in Storage-Battery Electrodes or Plates, of which the following is a specification.

10 The end construction of plates or electrodes which include metal rods surrounded by active material or material adapted to become active inclosed in insulating ribbed and perforated tubes, has been improved by 15 the use of a poured end-connecting bar, but drops of metal escaped from the mold in which the end bar was cast and remained upon the surface of the tubes and these drops of metal were detrimental to the 20 proper operation of the battery.

The principal object of the present invention is to avoid these drops of metal and to improve the end construction both as a finished product and in respect to the facility of its manufacture.

The invention will be claimed at the end hereof but will be first described in connection with the accompanying drawings forming part hereof and in which—

30 Figure 1 is an elevational view of a plate or electrode embodying features of the invention.

Fig. 2 is a bottom plan of the same.

Fig. 3 is a transverse section drawn to an 35 enlarged scale indicating also a mold, and

Figs. 4 and 5 are sections respectively on the lines 4—4 and 5—5 of Fig. 3.

In the drawings 1, are metal rods surrounded with active material or material 40 adapted to become active, 2, 3, is a poured end connecting bar, meaning that it is formed in the mold indicated at 4, in Fig. 3, and thus made and attached to the plate at one operation. When the metal is poured 45 the position of the parts shown in Fig. 3, is

of course inverted. 5, are ribbed and slotted insulating tubes inclosing the material 2, and provided at their ends with ribless cuffs 6, adapted to fit cylindrical mold cavities and so prevent the escape of molten metal, 50 even if the ends of the cuffs are at different levels. These cuffs may be slotted as shown at the left in Fig. 1, or imperforate as shown at the right in said figure, but they are ribless. Were the cuffs provided with 55 ribs commercial production of the plates would be greatly hampered since the slots in the mold to receive the ribs must be of exactly fitting dimensions to prevent escape of the molten metal, entailing a great expenditure of time in fitting each tube in its 60 recess in the mold and further increasing the difficulty of operation since a tube is likely to shift (being semi-elastic) while the others are being placed, so preventing the proper 65 closing of the mold, engendering crushing of the ends of the misplaced tubes and permitting leakage of the molten metal.

Furthermore since the tubes may be of slightly varying lengths a short tube in a 70 recessed mold would result in a continuation of the projecting rib in the metal casting which being a conductor instead of an insulator is not permissible.

The ribless cuff at the end of the tube, by 75 permitting the use of a mold with ribless cavity overcomes all the difficulties enumerated above.

I claim:

In a storage battery plate or electrode, including metal rods surrounded by active material or material adapted to become active, and in combination therewith, a poured end-connecting bar, and ribbed and slotted insulating tubes inclosing said material and 80 provided at their ends with ribless cuffs 85 adapted to fit corresponding mold cavities, substantially as described.

CORNELIUS AMBRUSTER.
